UNITED STATES PATENT OFFICE.

CHARLES BRUNNER, OF PERU, ILLINOIS.

PLATFORM-SCALE.

SPECIFICATION forming part of Letters Patent No. 451,613, dated May 5, 1891.

Application filed September 13, 1890. Serial No. 364,863. (No model.)

To all whom it may concern:

Be it known that I, CHARLES BRUNNER, of Peru, in the county of La Salle and State of Illinois, have invented certain new and useful Improvements in Platform-Scales; and I do hereby declare that the following is a full, clear, and exact description thereof, reference being had to the accompanying drawings, and to the letters of reference marked thereon, which form a part of this specification.

This invention relates to weighing-scales of the platform order, and has for its primary object to provide a construction by which the effects of expansion and contraction of the levers, resulting from changes in temperature, are obviated and greater accuracy attained.

It has for a secondary object to provide a construction for the suspension of the oscillating platform-supporting cross-bars of the lever system whereby their poise is rendered more sensitive.

In the accompanying drawings, which illustrate my invention, Figure 1 is a top or plan view, the platform being broken away at one end. Fig. 2 is an elevation seen from that side of the apparatus at which the scale-beam is located, the view being obtained by a removal of the side wall of the pit. Fig. 3 is a vertical transverse section in the line 3 3 of Fig. 2, looking in the direction indicated by the arrows applied to said line.

A represents a platform having two longitudinal beams A' A', which extend nearly the length of the pit B.

C C are oscillating bars for the support of the platform, being suspended across the ends of the pit from corner-irons D D. This suspension is effected by means of links c c, one at each end of each bar C, engaged with the corner-irons and with knife-edge bearing-pins c' passing through lugs c² c² on the upper sides of the bars and through the links c, as clearly shown in Fig. 3. Each cross-bar C

is provided with two upwardly-projecting flanges C' C', terminating in hardened knife-edges extending lengthwise of the bar, but located out of the central line of the suspending-pins c' on that side of the bar C toward the middle of the scale or platform. Upon these projections C' rest the beams A' A' of the platform, the latter being provided with

suitable "irons" or hardened-metal surfaces at the points of contact with said projections C'.

Each of the oscillating bars C is provided with a lever-arm, engaging, in the usual way, a stirrup E upon the lower end of the scale-rod E', by which the scale-beam is operated; but said lever-arms, instead of being continuous or severally integral, as ordinarily constructed, are made each in two parts which are so connected with each other as to permit a free lengthwise movement of one with respect to the other, while at the same time transmitting the power from the platform to the scale-rod. Such two parts of the lever-arms are shown clearly, in Figs. 2 and 3, to be composed of short portions or arms C², which are rigid with the cross-bars C and the extension-bars C³, engaged at their free ends with the stirrups E. As herein illustrated, the connection of the extension-bars C³ with the arms C², by which the desired lengthwise movement above referred to is permitted, consists in arranging the bars C³ above the arms C², giving sliding contact of the extremity of said bars C³ with the arms C², and applying links F to knife-edge cross-pins f f' between the point of contact of the bars C³ with the arms C², and the connections of said bars C³ with the scale-rod. By thus making the lever-arms in two parts having the possibility of free longitudinal movement with respect to each other the effect of expansion and contraction, which has been found to materially disturb the accuracy of the scale by elongating or shortening the integral lever-rods heretofore used, is obviated, and the scale is found to weigh with substantially uniform accuracy at varying temperatures.

Other modes of connecting the two parts of the several lever-arms C² C³ may be obviously employed with the same effect, and I therefore do not wish to be restricted to the specific construction of the connection herein illustrated.

I claim as my invention—

1. In a weighing-scale, the combination, with the platform and the scale-rod, of the oscillating-bar C, supporting the platform and provided with two-part lever-arms connecting with the scale-rod, the parts of each of said lever-arms having a connection with each other which permits free lengthwise move-

ment of one part with respect to the other, whereby expansion and contraction thereof are automatically compensated.

2. In combination with the oscillating bars 5 C, supporting the platform and provided with arms C², the bars C³, connecting with the draft-rod of the scale and arranged to bear at their opposite ends upon the arms C², and links connecting the arms C² at their extremities 10 with the bars C³ at points between the bear-

ings of the latter upon said arms C² and their connection with the draft-rod of the scale.

In testimony that I claim the foregoing as my invention I affix my signature in presence of two witnesses.

CHARLES BRUNNER.
